UNITED STATES PATENT OFFICE.

ROBERT T. BRIZZOLARA, OF NEW DORP, NEW YORK.

DEVICE FOR PRODUCING ICE CUBES.

Application filed May 5, 1928. Serial No. 275,454.

The present invention relates to a device for producing ice cubes on a block of ice while in the ice chamber of an ice-box, and has for its primary object to provide a simply constructed device which may be of any convenient and adaptable size for handling by the house-holder and so as to form, by the natural melting of the ice, a number of small sections or cubes of uniform size and shape 10 for table use.

More particularly, the purpose of the present invention is to provide certain improvements in that type of ice cube producing devices which embody grids or intersecting 15 plates adapted to rest at their edges on the block of ice, the improvements relating to uniformity in the melting of the sides of the ice cubes and in the equal distribution of the heat absorbed by the device and conducted 20 to the different sides of the cube and to the cutting or bearing edges of the grid.

Another object of the invention is to provide a device which insures drainage of melted water from about the walls and edges of 25 the grid, and a device which may depend solely upon pressure, such as by the weight of the device itself, and which may combine with the pressure the agency of heat for promoting melting of the ice to form the cubes.

30 The invention further contemplates the provision of draft regulating and heat distributing members as a part of the grid and which are adapted to lie in the path of the circulation of the warm air at the top of the ice chamber and to absorb from the air current the heat units and transmit them to the 35 portions of the grid which come into contact with the block of ice, the heat transmitting elements promoting rather than retarding the 40 circulation of the air in the ice chamber, so as to effect a uniform distribution of the heat.

With the above and other objects in view, the invention consists in the improved ice cube forming device and in the form, construction and relative arrangement of its several parts, as will be hereinafter more fully described, illustrated in the accompanying drawing and subsequently incorporated in the subjoined claims.

50 In the drawing, wherein I have illustrated one simple and practical embodiment of the device, and in which similar reference characters designate corresponding parts throughout the several views,—

55 Figure 1 is a sectional view through the upper portion of an ordinary ice-box such

as is used in a house-hold, and showing a device for forming ice cubes constructed according to the present invention in position on a block of ice in the ice chamber.

60 Figure 2 is an enlarged, longitudinal, sectional view taken through the ice cube forming device.

65 Figure 3 is a bottom plan view of the device.

Figure 4 is a transverse, sectional view taken through the device.

70 Figure 5 is a perspective view looking at the under side of the device, showing the ice cube forming compartments and the drainage projections at the sides and ends of the device, and

75 Figure 6 is a top plan view of the device. The ice cube forming device is in the form of a grid composed of a plurality of spaced, longitudinal plates 10 intersected by transverse spaced-apart plates 11. The plates 10 and 11 may be of any suitable length to provide the desired number of ice cube forming chambers 12 and with the chambers 80 12 of the desired size. The lower edges 13 of the plates 10 and 11 may be beveled or sharpened, as shown to advantage in Figures 3 and 4, so as to facilitate the melting of the ice by impact of the edges thereagainst.

85 The device is adapted to rest on top of a block of ice 14, shown in Figure 1, and with the lower edges 13 of the intersecting plates 10 and 11 bearing upon the ice for the purpose of collecting and concentrating heat absorbed by the device along lines of severance between the sections of the ice defined between the walls 10 and 11. The walls 10 and 11 are extended beyond the grid structure to provide wings 15 and 16, projecting from the 90 sides and ends of the grid, respectively. These wings 15 and 16 may project from all of the sides of the grid, as shown in the drawings, or they may project from but three sides, or even a less number of sides, although for 10 the purpose of accommodating the device to various inequalities in the upper surface of the ice block 14, it is preferable to provide the wings 15 and 16 at at least three sides. The wings, being co-extensive with the plates 10 and 11, are continuations thereof and are adapted to work into the surface of the ice block 14 and form grooves or channels through which water may escape which is produced by the melting of the ice beneath 110 and about the plates 10 and 11.

For the purpose of insuring a uniform

shape and size to the cube formed within the chamber 12, each chamber is provided with a closed top 17 for entirely closing the top of the chamber. The top 17 may be a portion 5 of a large plate which extends over all of the chambers or compartments 12 so as to reduce the number of joints required in the construction of the grid, and so as to more uniformly diffuse the heat absorbed by the grid. The 10 closed top 17 performs a dual function. It provides a stop for limiting the downward settling of the grid in the block of ice and determines the depth of the sections of ice which are segregated by the melting action. The 15 top 17 also uniformly distributes the heat over the upper surface of the ice cube and thus maintains the upper surface flat and in uniformity with the general configuration of the cube, so that the product produced is of a uniform 20 shape and size and has well defined flat faces and joining edges when the grid is removed.

To further insure the equal distribution of the absorbed heat throughout the grid, the 25 latter is provided with a number of air channels or passages 18 which are defined by spaced fins 19 which rise from the grid and which are preferably integral with the longitudinal strips 10. These fins 19 are preferentially co-extensive with the strips 10 so as to extend from end to end of the grid. The grid is adapted to be placed in the ice chamber of the ice-box, as shown in Figure 1, with the fins 19 extending lengthwise of the direction or path of travel of the air current in the 30 upper end of the ice chamber so that the fins will offer practically no resistance to travel of the air as it passes across the top of the block of ice 14 and across the top of the grid. The 35 fins 19, however, are adapted to absorb the heat from the air as it flows from the top of the food compartment and to transmit its heat downwardly through the strips 10 and 11 and to the top wall 17. As there is practically no 40 resistance to the flow of the air through the channels 18, the fins 19 are effective throughout their entire length in absorbing the heat from the air so that the remote end of the grid is maintained at substantially the same temperature as is the proximate end with reference to the direction of the flow of air. In 45 this manner the melting of the ice beneath the grid is uniform throughout the length and breadth of the grid. It will be noted that the wings 15 and 16 may be left open at their 50 upper ends so that the air is free to flow downwardly between the fins and the latter may absorb heat from the air as it passes downwardly against the outer sides of the lateral fins 19. This also serves to uniformly 55 distribute the heat to the strips 10 and 11.

The wings 15 and 16 need not of necessity be of the same length or breadth as the walls of the compartments 12, it being necessary 60 only that the wings 15 and 16 lie in substan-

tially the same planes as the lower edges of the strips 10 and 11, so as to form the drainage grooves in the upper surface of the block of ice.

It is apparent that the weight of the grid 70 with its wings 15 and 16 and the fins 19 is sufficient to cause the melting of the ice along the lines of the lower edges of the strips 10 and 11. The grid may be additionally weighted, however, if desired, and suitable 75 heating means may be used, such as electrical or otherwise, for promoting the melting action. The grid and its parts are made of suitable metal to not only lend weight to the structure but to also transmit heat absorbed 80 from the air current to the cutting edges of the grid and to the walls defining the chambers or compartments 12. The tops or walls 17 provide a barrier or a stop for limiting the downward movement of the grid during the 85 melting action, although should the grid be left in place even after the full-sized cubes are formed in the compartments 12, the uniform distribution of heat throughout the top 90 17 is such that while the action is retarded still the further melting of the ice does not distort the form or shape of the cubes in the compartments 12.

The water produced by the melting of the 95 ice is permitted to drain off from beneath the grid along the channels formed in the upper surface of the block 14 of ice as the wings 15 and 16 project sufficiently beyond the sides of the ice block to open the channels or grooves therethrough, the water draining down the sides of the block of ice. This draining of the water prevents such accumulations around the edges of the strips 10 and 11 as would seriously affect the shape or form of the ice cubes by the transmission of the heat through 100 the accumulated water to the sides of the ice cubes at points above the biting or cutting edges 13.

An important feature of the structure is the 105 continuity and uniformity in the structure of the five walls of each compartment 12, so that there will be an even distribution of heat about the block and the melting will be uniform at the top as well as at the sides. When the cubes are formed in the compartments 12, the device may be lifted from the block of ice 14, and the individual cubes be split or otherwise severed individually from the block as they are needed.

If the grid of this invention is fitted to 120 the top of a block of ice where there is no means of directing or providing an air current, it will be found that the absorption of the heat from the surrounding air will be uniform throughout the length and breadth 125 of the grid, the fins 19 serving not only in this instance but to also uniformly diffuse the heat throughout the grid in the presence of an air current when the latter flows in the channels 18.

Accordingly, it is to be understood that in the further development of my invention, I reserve the privilege of resorting to all such legitimate modifications in the form, construction and relative arrangement of the various elements as may be fairly incorporated in the spirit and scope of the invention as claimed.

I claim:

- 10 1. An ice cube forming grid comprising two series of heat absorbing metal plates, the plates of one series being transverse to the plates of the other series and rigidly connected therewith to thereby form a plurality of chambers, said grid adapted to be arranged upon an ice block to melt the same and said elements of the grid sinking into the block to thereby form a plurality of ice sections in the chambers of the grid adapted to be subsequently separated from the body of the ice block, a top plate carried by said metal plates and extending across the tops of said chambers to completely close said chambers at their upper ends and uniformly engage the upper surfaces of said ice sections, and fins extending beyond said grid and beyond the ice block to which the grid is applied.
- 15 2. An ice cube forming grid comprising spaced longitudinal and transverse metal strips disposed in intersecting relation to provide chambers therebetween, a top plate carried by said strips for closing the tops of said chambers, wings projecting beyond the ends of said strips and forming continuations of the lower edges of said strips, and spaced fins extending upwardly from said strips and said top plate providing air channels between the fins adapted to receive currents of air therethrough.
- 20 3. An ice cube forming grid comprising spaced longitudinal and transverse strips disposed in intersecting relation to provide ice cube compartments, a top plate carried by said strips for closing the tops of the compartments, fins projecting upwardly from the longitudinal strips and spaced apart above the top plate to provide air receiving channels, and wings projecting from the sides and

ends of the grid and forming elongations of the lower edges of the strips.

4. A device of the character described comprising a grid consisting of two series of heat absorbing metal plates, the plates of one being transverse to the plates of the other series and rigidly connected therewith to thereby form a plurality of chambers, said grid adapted to be arranged upon an ice block to melt the same, and said elements of the grid sinking into the block to thereby form a plurality of ice sections in the chambers of the grid adapted to be subsequently separated from the body of the ice block, a top plate carried by said metal plates and extending across the tops of said chambers to completely close said chambers at their upper ends and uniformly engage the upper surfaces of said ice sections, and fins extending beyond said grid and beyond the ice block to which the grid is applied.

5. A device of the character described comprising a grid consisting of two series of heat absorbing metal plates, the plates of one series being transverse to the plates of the other series and rigidly connected therewith to form a plurality of chambers, a top plate extending over said first plates to close in the tops of said chambers, the said first plates extending in one direction of the grid projecting upwardly beyond the top plate to provide heat absorbing fins and air channels between the fins.

6. A device of the character described comprising a grid consisting of two series of heat absorbing metal plates, the plates of one being transverse to the plates of the other series to form a plurality of chambers therebetween and with the extremities of the plates projecting beyond the grid to provide drain groove forming wings, a top plate secured across said first plates for closing in the tops of said chambers, and spaced fins projecting upwardly from said first plates beyond the top plate and in one direction only across the top of the grid to provide between the fins air channels adapted to align with the path of travel of air currents over the top of the grid.

In testimony that I claim the foregoing as my invention, I have signed my name hereto.

ROBERT T. BRIZZOLARA.
